UNITED STATES PATENT OFFICE.

LINDLEY S. LAWSON, OF PITTSBURGH, PENNSYLVANIA.

DESIGN FOR A GAS STOVE.

Application filed February 10, 1923. Serial No. 5,146. Term of patent 3½ years.

To all whom it may concern:

Be it known that I, LINDLEY S. LAWSON, a citizen of the United States, and residing at Pittsburgh, in the county of Allegheny and State of Pennsylvania, have invented a certain new, original, and ornamental Design for a Gas Stove, of which the following is a specification, reference being had to the accompanying drawing, forming a part

thereof, which is a front view in elevation of a gas stove embodying this design.

I claim:—

The ornamental design for a gas stove substantially as shown.

LINDLEY S. LAWSON.

Witnesses:

EDNA SCHINKLE,

IDA L. SHERRER.
